(57) **CLAIM**

The ornamental design for a silicone support frame for air mask as shown and described.

DESCRIPTION

FIG. 1 is a front left perspective view of a silicone support frame for air mask, showing my new design;

FIG. 2 is a rear, right, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.

The broken lines in the figures are for the purposes of illustrating portions of the silicone support frame for air mask, which form no part of the claimed design.

1 Claim, 8 Drawing Sheets
